UNITED STATES PATENT OFFICE.

HERMAN L. MARBACH, OF LORAIN, OHIO, ASSIGNOR OF ONE-HALF TO
ORVILLE P. MOON, OF SAME PLACE.

VALVE MECHANISM.

SPECIFICATION forming part of Letters Patent No. 631,650, dated August 22, 1899.

Application filed March 11, 1898. Serial No. 673,457. (No model.)

To all whom it may concern:

Be it known that I, HERMAN L. MARBACH, a citizen of the United States, residing at Lorain, in the county of Lorain and State of Ohio, have invented certain new and useful Improvements in Valve Mechanism; and I do declare that the following is a full, clear, and exact description of the invention, which will enable others skilled in the art to which it applies to make and use the same.

My invention relates to valve mechanism, and is here shown as applied to vapor-burners, but it may be used elsewhere as well.

The object of the invention is to automatically control the inflow of the fluid—in this case to the burner—and to allow only a certain quantity of fluid or liquid to be retained in the stand-pipe until a portion is used up. This assures a more regular feed or supply of the fluid than is otherwise attainable and prevents an overflow thereof through the needle-valve, thereby obviating all possible danger from waste or explosion on this account, as well as also avoiding disagreeable annoyances resulting from such overflows.

In the accompanying drawings, Figure 1 illustrates a vapor-burner connected to a stand and feed pipe, as is usual in this art, with the valve mechanism at its bottom in section. Fig. 2 is a sectional elevation of the lower part of the so-called "stand" portion of the mechanism, enlarged, and the feed-pipe with my improved valve therein, the valve and its parts being also in vertical section. Fig. 3 is a similar view to Fig. 2, but showing the valve mechanism only partly in section and open to the inflow of liquid. Fig. 4 is a modification wherein weights are used instead of springs, as shown in Figs. 2 and 3.

40 A represents a hydrocarbon-burner, such as is commonly used in vapor-stoves, particularly of the gasoline type.

B is the stand-pipe, fixed to the bottom of the burner, and C the feed-pipe, through which the liquid is conveyed to the burner by pressure or otherwise.

Heretofore the usual method of cutting off the supply of liquid or vapor has been by means of a needle-valve D; but with my construction I employ the needle-valve D only to control the flow of vapor to the burner

and provide an automatic valve E within the stand-pipe B to control the flow of the liquid. The said valve E is dependent for its position on the quantity of liquid in the stand-pipe B 55 and is opened, primarily, through a floating weight F in the stand-pipe subject to rise and fall with the oil, and, secondarily, the valve is subject to the springs 5 and 7, the weight F being of such size and displacement as 60 to rise and fall with the liquid as it is first fed in and then converted into vapor, as explained farther on. When the valve is open, the liquid flows in past the same, and as the liquid rises in the stand-pipe and partially 65 submerges the weight F it causes the weight to rise in the same proportion until it is taken entirely off the valve. This of course allows the spring 5 to force valve E up to its seat, thus preventing any further flow of fluid into 70 the stand-pipe for the time being; but after a portion of the liquid in the stand-pipe has been converted into vapor and carried off the weight descends again and opens valve E, and the liquid is again free to flow into the 75 stand-pipe to a certain height, when the valve is again closed, as in the first instance, and this is automatically repeated while the burner is in operation. The construction of the valve E to accomplish this end is as follows: A tube 2 is attached to the feed-pipe connection C, and a valve-seat 3 is provided at the bottom thereof for said valve. The valve itself has an upwardly-extending stem 4, with an enlarged head at the top thereof, 80 (also marked 4,) and said head closes and is free to slide in the top of the guide-tube 2. A spring 5 is interposed between this head and the lower portion of the tube 2, and the spring 5 keeps the valve normally closed until 85 opened by the sliding cover 6, which is directly engaged by the weight F. The cover 6 sleeves over the stem 2 and is free to slide up and down thereon, and a spring 7 is located in the bottom thereof, which bears 90 against shoulder 8 in the cover and the collar 9 on the outside of stem 2. A screw 10 through cover 6 below the collar 9 limits the upward movement of the cover in respect to the other parts. Openings 12, located at the 100 bottom of the tube 2, allow the liquid to pass out into the stand-pipe B.

The weight F is of such size and displacement as to rest at all times on the top of cover 6, and the object of the spring 7 is to keep the said cover a sufficient distance away and 5 above the head of the spindle, so that a fairly free up-and-down movement of the cover and weight can be accommodated without striking the head of stem 4, and thereby cause the valve to open, even though it be but momentarily. This momentary opening of the valve is liable to occur through the vibration, shaking, and possible uncertain foundation of the stove unless some such means as described are provided.

15 When a certain portion of the liquid within the stand-pipe B has been converted into vapor and allowed to escape, the weight F will press the cover or casing 6 down until its top strikes the head of the stem 4 and opens valve 20 E. The liquid will then flow into the stand-pipe until it lifts the weight up high enough to allow spring 5 to close valve E.

In Fig. 4 a modification is shown which substitutes counterweights in lieu of springs 5 25 and 7. In this case there is pivoted to the top of valve-stem 4 a cross-piece 14, which rests normally on the top edge of tube 2 and carries a counterweight 15, suspended from the outer end thereof. A counterweighted 30 arm 16 is pivoted at the side and top of tube 2 and has an extension 17 above its pivot on which the weight F normally rests, the same as it does on cover 6 in Figs. 2 and 3, and the counterweighted arm 16 and 17 serves all the 35 purposes of cover-casing 6. When the weight F descends, it offsets the counterweight of arm 16, which at the most is very light, and the weight F then in its further descent strikes the extremity 18 of cross-piece 14 and the 40 valve E is depressed and opened.

What I claim is—

1. A vapor-burner having a supply-pipe, a

spring-pressed valve controlled by the rise and fall of the liquid within said pipe, a cover over the valve-stem arranged to bear on the 45 stem to open the valve, and a weight adapted to operate the cover to open the valve, substantially as described.

2. A vapor-burner and oil-supply pipe beneath the same, an upwardly-seating valve in 50 said pipe to control the flow of the liquid to the burner, a cover over said valve in said pipe, a weight in the oil-supply pipe adapted to bear on said cover, and separate springs connected with the said valve and cover to 55 raise said parts, substantially as described.

3. A vapor-burner and an oil-supply pipe therefor, in combination with an inlet-tube in said pipe having a valve-seat at its bottom and a valve and valve-stem in said tube, a 60 weight in said pipe above said valve-stem and means between said stem and said weight to take up the vibrations of the weight and thus prevent accidental opening of the valve, substantially as described.

4. A vapor-burner having a stand-pipe secured to the bottom thereof, and a supply-pipe connected with the stand-pipe, in combination with a downwardly-opening valve in the supply-pipe, a free floating weight in the 70 stand-pipe, a stem on said valve and means connected with said stem to hold the valve normally in closed position, and interposed mechanism between the valve-stem and the floating weight to take up the vibrations and 75 prevent accidental opening of the valve, substantially as described.

Witness my hand to the foregoing specification this 25th day of January, 1898.

HERMAN L. MARBACH.
